OF CHICAGO, ILLINOIS, A CORPORATION OF ILLINOIS.

STENCIL-PRINTING DEVICE

1,234,310.

Specification of Letters Patent. Patented July 24, 1917.

Application filed March 5, 1915. Serial No. 12,276.

To all whom it may concern:

Be it known that I, JOSEPH S. DUNCAN, a citizen of the United States, residing at Chicago, in the county of Cook and State of Illinois, have invented certain new and useful Improvements in Stencil-Printing Devices, of which the following is a specification.

This invention relates to stencil printing devices of the kind adapted for use in addressing machines and the like.

Heretofore stencil printing devices have been made with a single opening in the frame covered with stencil paper and of a size sufficient to accommodate little if anything more than an address. It has not been considered practical to make the device large enough to accommodate, in addition to the address, the many different items of information which the trades desire to print or provide for printing along with the address, because of the character of the materials employed in making the stencil. For example, an insurance company desires to print information relating to the policy along with the policy holder's address and a tax collector desires to print the legal description of the property along with the owner's address. It is not practicable to embody such information with an address upon stencil paper over a single opening in a frame, especially when the information or the address is lengthy, because it requires too great an area of stencil paper and too large a frame with a single opening and such a device would not be substantial and would not stand the usage to which address stencils are subjected.

The object of this invention is to combine an address stencil and an information stencil in a single frame of substantial construction and adapted to be stored in accordance with a card index system and used in addressing machines.

45 In the accompanying drawings

Figure 1 is a front elevation of the stencil;

Fig. 2 is a back view; and

Fig. 3 is a sectional view on line 3—3 of 50 Fig. 1.

The device comprises a one-piece frame 5 having two oblong impression openings 6 and 7 located one above the other and separated by the partition 8. This partition 55 may be located in any position between the

top 9 and bottom 10 of the frame but preferably midway and the openings 6 and 7 are preferably of about the same width and length, although they may be varied to suit different conditions.

A sheet 11 of stencil paper is affixed to one side of the frame preferably by pasting it securely to the entire surface of the frame with its edges flush with the top, bottom and side edges of the frame. It is not necessary that the edges of the paper shall extend entirely to the edges of the frame, although it is better that they should extend as close to the edges of the frame as convenient to obtain the greatest amount of pasting surface. 65 In Fig. 2 I have shown the edges of the paper slightly within the edges of the frame. Stencil paper is tough and pasting it to the frame along all its edges and across its middle not only secures the paper permanently to the frame but materially strengthens the frame. This enables me to make a strong and substantial frame out of comparatively thin paper stock, like pasteboard, card-board, or other suitable material, notwithstanding the size of the frame and the two large openings therein. The partition supports the paper and holds it taut while at the same time it constitutes a 75 stiffener for the frame.

Index tabs of any suitable character may be used with the device and for this reason I prefer to provide each frame with the integral upstanding corners 12 to protect the tabs when the device is passing through the 80 addressing machine. While the stencil paper may be pasted over the tabs also this is not necessary and it will be found more economical not to do so.

The address may be provided on the stencil paper over the upper opening 6, or the lower opening 7, and the information likewise. Sometimes it may be desirable to provide more space for the address than for the information, or vice versa, and in that event 85 one opening may be made wider than the other. It will be readily understood that a single device made in accordance with my invention may carry a great deal of useful information in addition to an address of 100 several lines, thereby increasing the uses for which address stencils may be employed. This arrangement of the address in an opening and the information in a separate opening of the single frame is important as it 105 110

enables an impression to be taken from either or both as desired without liability of confusion.

The construction of the device comprising a one-piece frame with a single sheet of stencil paper covering both impression openings and affixed at its edges and across its middle to the frame, is important because it provides a light and thin but substantial device which will hold its shape and stand any ordinary usage to which it may be subjected. As the devices are intended to be fed one by one from a stack in the addressing machine, and usually from the bottom of the stack, step by step to printing position and then to be discharged into a drawer, it is most essential that they shall not easily bend or warp or wear. In my device the frame carries the stencil and holds it taut and the stencil strengthens the frame. This strengthening of the frame is important because of the size and skeleton character of the frame and it is efficiently and economically accomplished by the single sheet of stencil paper pasted thereon. Furthermore, the front of the device lies in a single plane and because the stencil paper covers practically the entire back of the device it may be said that the back of the device lies almost wholly in a single plane, thereby providing a device which is flat,

without surface projections and which can easily be fed through the addressing machine.

I claim:

1. A stencil printing device comprising a one-piece frame of paper stock having two oblong impression openings disposed one above the other and separated by a relatively narrow strip integral with said frame, and a sheet of stencil paper adhesively secured to substantially the entire back of said frame and covering said openings, whereby separate stencil printing sections are provided and said frame is stiffened. 45

2. A stencil printing device comprising a one-piece frame of paper stock having two oblong impression openings disposed one above the other and separated by a relatively narrow strip integral with said frame, a sheet of stencil paper adhesively secured to substantially the entire back of said frame and covering said openings whereby separate stencil printing sections are provided and said frame is stiffened, 55 and projecting tabs projecting from the upper edge of said frame at both ends thereof. 50

JOSEPH S. DUNCAN.
